UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

EIGHT-DAY ALARM-CLOCK.

1,156,552.

Specification of Letters Patent.

Patented Oct. 12, 1915.

Application filed June 19, 1914. Serial No. 846,202.

To all whom it may concern:

Be it known that I, WILSON E. PORTER, a citizen of the United States, residing at New Haven, in the county of New Haven and 5 State of Connecticut, have invented a new and useful Improvement in Eight-Day Alarm-Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in front elevation of an 15 alarm-clock constructed in accordance with my invention with a portion of the dial broken away and the alarm-stop plunger and a portion of the case in vertical section, the parts being shown in position to sound 20 an alarm. Fig. 2 a detached view in front elevation of the movement showing the alarm-stop plunger in engagement with the combined alarm-stop and alarm let-off lever. Fig. 3 a plan view of the movement. 25 Fig. 4 a perspective view of the alarm-stop plunger. Fig. 5 a detached perspective view of the combined alarm-stop and alarm let-off lever.

My invention relates to an improvement 30 in that class of eight-day alarm-clocks in which a continuous alarm is sounded until stopped by the manual operation of a push-button which is automatically released by the time-mechanism within the twenty-four 35 hours next succeeding the sounding of an alarm, so that the clock is automatically restored to readiness for sounding the alarm, though manually operable for shutting off the alarm, the object being to provide a 40 clock of the character described with a simple and effective shut-off constructed and arranged with particular reference to convenience and reliability of operation.

With these ends in view, my invention 45 consists in an eight-day alarm-clock having certain details of construction and combinations of parts as will be hereinafter described and particularly recited in the claims.

50 In carrying out my invention as herein shown, I locate an alarm-stop 2 in the form of a conical head at the lower end of a plunger 3 the upper end of which is formed with a threaded stem 4 for the application 55 to it of a slotted circular head 5 which re-

ciprocates in the upper end of a vertically arranged circular housing 6 having its upper end riveted into the inner shell 7 of the clock-case at a point coincident with the vertical center thereof. The said housing 6 60 has its lower end centrally perforated to provide a bearing for the plunger 3 and receives a helical spring 8 the upper end of which bears against the inner end of the slotted head 5 and exerts a constant effort to lift the 65 plunger 3 and head 5 into their elevated or retracted positions. The upward movement of the plunger 3 is limited by the engagement of the upper face of the stop 2 with the lower end of the housing 6. The said head 5 70 is impinged by an annular shoulder 9 located at the lower end of a push-button 10 having bearing in a bushing 11 mounted in the outer shell 12 of the clock-case and retained in place by a nut 13 applied to its 75 inner end. The said push-button 10 as thus arranged, is located in the center of the top of the clock-case which, as shown, is provided with a flattened bow 14 having its ends pivoted in bow-posts 15. The alarm-stop 2 aforesaid is located directly above the inner edge of a horizontal stop-arm 16 turned inward at a right angle from the upper end of an oscillating combined alarm-stop and let-off lever 17 swinging upon a 80 stud 18 passing through its lower end and mounted in the front movement-plate 19. The said lever 17 is formed upon its left hand edge with a lateral arm 20 from which a finger 21 is turned forward at a right 85 angle for co-action with a cone 22 located upon the inner face of a laterally movable alarm-cam wheel 23 the forward face of which is provided with an alarm-cam 24 co-acting with a pin 25 mounted in the forward 90 end of an alarm-set staff 26 which projects forwardly through the front movement-plate 19 and rearwardly through the rear movement-plate 27 and is furnished at its 95 rear end with a finger-button 28. At its extreme forward end, the staff 26 is furnished with an alarm-set wheel 29 which meshes into and drives a set-pinion, not shown, but loosely mounted upon the hour-hand socket 30 and carrying an alarm-set pointer 31. A 100 helical spring 45 interposed between the front movement-plate 19 and the cone 22, operates to push the same and the alarm-cam wheel 23 sharply forward when the cam 24 drops off the pin 25. A helical 105 110

spring 32 connected with the plate 19 and the upper end of the lever 17, exerts a constant effort to pull the lever from right to left and so maintain the finger 21 in contact 5 with the cone 22.

The stopping of the alarm-train by the lever 17 is effected by the engagement of the outer edge of the arm 16 thereof with the hooked outer end of a vibrating stop-wire 33 mounted in the verge-arbor 34 and rocking therewith, the said arbor also carrying an alarm cut-out arm 35, a hammer wire 36 carrying a hammer 37, and a pallet 38 co-acting with an escapement-wheel 39 mounted upon an escapement-shaft 40 carrying an escape-pinion 41. The rear movement-plate 27 is provided with a three-armed cut-out lever having an arm 42 adapted to co-act with the cut-out wire 35, with a stop-arm 43 co-acting with the upper edge of the rear movement-plate 27, and with a rearwardly projecting manually operable arm 44 which is designed to project through the back of the clock-case.

When the alarm-train is let-off in the ordinary manner by the action of the time-train, an alarm will be continuously sounded with the parts in the positions shown in Figs. 1 and 3 in which it will be seen that the hooked outer end of the stop-wire 33 clears the outer edge of the stop-arm 16 of the lever 17.

To stop the sounding of the alarm, it is only necessary for the user of the clock to press down upon the push-button 10, whereby the conical, button-like alarm-stop 2 is crowded against the left hand or inner edge of the stop-arm 16, causing the lever 17 to be swung from left to right against the tension of the spring 32 and the outer edge of its stop-arm 16 carried into the path of the hooked outer end of the stop-wire 33. This will stop the sounding of the alarm. At the same time the stop 2 rides over the left hand edge of the stop-arm 16 which is then by the action of the spring 32, hooked over the stop, as it were, as shown in Fig. 2, whereby the stop, is prevented against the tension of the helical spring 8, from rising, and remains in position to hold the lever 17 in its alarm-stop position. During the next few hours, the time-mechanism by causing the inward movement of the alarm-cam wheel 23 pushes the cone 22 against the finger 21 of the arm 20 of the lever 17 which is gradually swung from left to right sufficiently to disengage the stop 2 which is then restored to its normal position by the spring 8. The cone 22 now acts to hold the lever 17 in position to restrain the sounding of the alarm until the termination of the twenty-

four hour cycle at the conclusion of which the alarm will be automatically sounded in the ordinary manner by the dropping of the cam 24 off the pin 25. The alarm will now 65 be continuously sounded until the user of the clock pushes the button 10 downward to reengage the alarm-stop 2 with the combined alarm-stop and left-off lever 17.

I claim:—

1. In an eight-day alarm clock, the combination with the case thereof, of a clock-movement comprising time and alarm-mechanisms, the latter having a stop-member, of a combined alarm-stop and alarm let-off lever, operated by the said time-mechanism, and a 75 plunger directly engaging the said lever for moving the same into position for being directly engaged by the said stop-member for stopping the said alarm-mechanism, the said lever and plunger co-acting to hold the said lever in position to restrain the alarm-mechanism until the lever is automatically released from the plunger by the action of the time-mechanism.

2. In an eight-day alarm clock, the combination with the case thereof, of a clock-movement comprising time and alarm-mechanisms, the latter having a stop-member, of a combined alarm-stop and alarm let-off lever, means for operating the same periodically by the time mechanism, a plunger mounted in the said case in position to directly engage the said lever for moving the same into position for being directly engaged by the said stop-member for stopping the alarm-mechanism and hence the alarm, the said plunger and lever co-acting to hold the lever in its alarm-restraining position until the said lever is automatically released from the said plunger by the time-mechanism.

3. In an eight-day alarm clock, the combination with the clock case, of time and alarm mechanisms, the latter including an alarm-wheel provided with an alarm-cam and operating cone, a lever adapted to be moved in one direction by the said cone, a spring for moving the lever in the opposite direction, a plunger connected with the clock case and provided with a conical head for co-action with the lever which is moved by the said head into its alarm-stop position and which is released from the said head by the action of the time mechanism.

In testimony whereof, I have signed this 115 specification in the presence of two subscribing witnesses.

WILSON E. PORTER.
